UNITED STATES PATENT OFFICE.

FRANK LEROY HILL, OF CHICAGO, ILLINOIS, ASSIGNOR TO BODINE ELECTRIC COMPANY, OF CHICAGO, ILLINOIS, A CORPORATION OF ILLINOIS.

DESIGN FOR A LOOP AERIAL.

Application filed July 22, 1926. Serial No. 18,450. Term of patent 14 years.

To all whom it may concern:

Be it known that I, FRANK LEROY HILL, a citizen of the United States, residing at Chicago, in the county of Cook and State of Illinois, have invented a new, original, and ornamental Design for a Loop Aerial, of which the following is a specification, reference being had to the accompanying drawings, forming part thereof.

Fig. 1 is a front elevation of a loop aerial, showing my new design.

Fig. 2 is a partial side elevation of the new design shown in Fig. 1.

I claim:

The ornamental design for a loop aerial, as shown.

FRANK LEROY HILL.
